ELECTROMAGNETIC FLUID PUMP

Nat H. Gedbold, Idaho Falls, Idaho, assignor to
the United States of America as represented
by the United States Atomic Energy Commis-
sion

Application August 29, 1956, Serial No. 182,121

4 Claims. (Cl. 163-1)

1

This invention relates to electromagnetic fluid pumps of the type in which an electrically conducting fluid is impelled along a channel by the magnetic force which results from an electric current passing through the fluid in a magnetic field and, more particularly, this invention relates to an improved electromagnetic fluid pump in which the magnetic force is utilized to cause a rotational motion of a liquid mass and the pressure head is obtained from the centrifugal force resulting therefrom.

In general, the electromagnetic fluid pump is old in the art and is shown, for example, in Patent 2,397,785 to Friedlander and in Patent 1,298,644 to Chubb. Such pumps of the prior art develop an impelling pressure head by the direct force developed between an electric current passing through the fluid and an externally impressed magnetic field.

It has been found that, although the electromagnetic fluid pumps of the prior art are effective and advantageous in many respects over other known types of pumps, they are inadequate to provide sufficient volume of flow or sufficient pressure for many applications.

It is, therefore, the primary object of this invention to provide an electromagnetic fluid pump which is capable of higher volumetric capacity and pressure generation than those heretofore known.

Other objects of the invention will appear from the following description wherein is explained that form of the invention which has been selected for illustration in the drawings accompanying and forming part of this specification.

These objects are obtained in the electromagnetic fluid pump of the present invention by utilizing the electromagnetic principles upon which the devices of the prior art are based in a novel manner. In the prior art, it is accepted as a cardinal principle that the direction of current flow in the fluid must be perpendicular to the direction of fluid flow. In the present invention, the direction of current flow is aligned with the direction of fluid migration or flow. Within the electromagnetic region of the device, the current in the fluid is caused to rotate under the influence of rotation of the magnetic field. Therefore, in this region, motion of the fluid is normal to the direction of current flow but this effect is used indirectly for propulsion in that the rotary momentum of the fluid mass is made available for propulsion by reason of the centrifugal force developed. The advantage of this arrangement lies in the fact that the fluid in the electromagnetic region is

2

subjected to the accumulation or integration of energy limited only by the attainment of a rotational velocity approximating the angular velocity of the impressed magnetic field.

5 In the drawings:

Figure 1 is a longitudinal cross sectional view of a preferred embodiment of the electromagnetic pump of the present invention and Figure 2 is a partial section taken on plane 2-2 of Figure 1.

Referring to Figure 1, a magnetic structure is shown to comprise a circular core 11 shown in cross section and an annular core 8 likewise shown in cross section. Interwound with the core element 8 is a polyphase electric winding 10 which, when energized, creates a rotating magnetic field in the magnetic structure. A fluid duct 14 is provided to channel the conducting fluid to be pumped through the magnetic structure in such a manner that it is subjected to the influence of the magnetic field. This duct comprises a tube portion 15 which axially threads the core structure 11. At the end of the core structure, the duct flares omnidirectionally outwardly to form a bell-shaped channel 16. An elongated annular channel 17 which may be cylindrical is provided between the core structures 8 and 11. The annular channel connects with the outer end of the bell-shaped channel 16. At the end of the core structure opposed to the bell-shaped channel, a conducting member 20 is provided. A second bell-shaped channel is provided in the conducting member 20 and connects at its small end with the exit end of the annular channel. The duct portion 15 is defined by a conducting tube 12 which is in intimate electric contact with end member 20. It follows that a closed electric circuit is established by the fluid through that portion of a fluid channel which is supported in the magnetic structure and the conducting end member 20. This closed circuit permits the creation of induced longitudinal currents in the fluid in the same manner as currents are induced in the rotor conductors of an induction motor with the result that reaction of the currents with the rotating magnetic field causes rotation of the fluid.

Fluid flow is initially accomplished by causing a rotating motion of the fluid in the bell-shaped channel 16. This is effected by providing a low hysteresis pole piece element 21 on the end of the core portion 11 and adjacent channel portion 15. On the opposing or outside boundary of channel 16, a ring-shaped extension 25 of the magnetic core 8 is provided. The open center of the ring extension is closed by a non-magnetic end cap 23.

There is thus established between the core extension portions 21 and 25, a rotating magnetic field. Fluid admitted into the duct through channel 15 into channel 16 is caused to rotate or whirl in the bell-shaped channel 16 by reason of drag between the electric currents induced in the fluid and the revolving impressed magnetic field. The whirling of the fluid in bell-shaped portion 16 gives rise to centrifugal force which impels the fluid into the annular core space 17 between the magnetic core portions 8 and 11. In channel 17, the fluid is caused to rotate in induction motor fashion and attains a high rotational velocity. The fluid passes from the annular channel 17 into the flaring or second bell-shaped channel 18. The energy stored in the fluid as rotating momentum is effective as a centrifugal force in the second bell-shaped channel 18 with the result that the fluid is impelled to the outer limits of the channel to exit port 19. The exit port 19 is more clearly seen in Figure 2 to merge tangentially with the outer portion of second bell-shaped channel 18.

It has been found that meritorious results are obtained by fabricating the pole piece element 21 of powdered iron compacts which increase the magnetic flux across the outer part of bell-shaped channel portion 16 while minimizing eddy current losses. To the end that eddy current losses are minimized, the core elements 8, 11 and 25 are composed of magnetic steel laminations.

While there has been herein described what is at present considered to be a preferred embodiment of this invention, it will be apparent to those skilled in the art that various changes and modifications may be made therein without departing from the spirit of the invention and, it is therefore intended that the appended claims cover all such changes and variations as are embraced within the spirit and scope of the invention.

What is claimed is:

1. An electromagnetic fluid pump comprising an annular polyphase magnetic structure and a fluid duct, said annular magnetic structure comprising an outer annular magnetic member and an inner annular magnetic member, said members being supported with a space therebetween, a polyphase electrical winding supported on the magnetic structure to create a rotating magnetic field which radially traverses the space between the magnetic members, said fluid duct having a first diverging portion, a second diverging portion, and an annular portion, said annular portion being connected at one end to the larger extremity of the first diverging portion and at the other end to the smaller extremity of the second diverging portion, said fluid duct first diverging portion and annular portion being supported at least in part in the space between the outer and inner members of said magnetic structure, said first diverging portion smaller extremity being a fluid inlet and said second diverging portion larger extremity being a fluid outlet, means electrically connecting the free end of the diverging portion and annular portion whereby said pump when electrically energized is adapted to cause rotation of electrically conductive fluid in said duct.

2. An electromagnetic fluid pump for generating a constant impelling pressure on an electrically conducting fluid, said pump including a magnetic core structure, a polyphase electric winding and a fluid duct; said magnetic core structure comprising an inner cylindrical core

element and an outer annular core element superposed over and radially spaced from said inner core element by the width of a fluid channel, said electric winding being interwound on the outer annular core so as to create under a condition of energization a substantially radial rotating flux traversing the fluid channel, said duct comprising a first portion being tubular and threading the inner core element, a second portion of bell shape connected at its small end to an end of the first portion and a third portion being the channel space between the core elements being connected at one end to the outer portion of said bell-shaped portion, a fourth duct portion of outwardly flared shape being connected at the smaller end thereof to the second end of said third duct portion; an electrical conducting element connecting the adjacent ends of the first and fourth duct portions, the other end of the duct first portion being a fluid inlet, and a fluid outlet port connected to the large end of the fourth duct portion.

3. In an electromagnetic fluid pump comprising a magnetic structure having a first and a second core element and a polyphase electric winding, and a fluid channel having a first, second and third portion; said first core element being elongated and of generally circular outer configuration in a direction normal to the elongation thereof, said second core element being elongated and generally circular in configuration normal to the elongation thereof and having an inner boundary with a radius greater than the outer radius of the first core element by the thickness of the fluid channel second portion, said second core element being supported to surround the first core element, said electric winding being supported on at least one of the core elements to produce under a condition of energization a rotating magnetic field which traverses the fluid channel in a direction substantially normal to the opposed surfaces of the first and second magnetic core elements, said fluid channel first portion being a bell-shaped duct supported adjacent a first end of the first core element, said fluid channel second portion being an elongated duct of generally circular shape in cross section nested between the first and second core elements, said bell-shaped duct being connected at its large end to a first end of the second duct portion, said fluid channel third portion being a flaring duct connected at the smaller end to a second end of the second duct portion, a circular magnetic extension element affixed to the second core element to overhang the first core element first end, and fluid conveying means connected to the inner end of the bell-shaped duct, means for electrically connecting the fluid channel first and third portions, whereby under a condition of electrical energization, a rotating field traverses part of the bell-shaped duct and the fluid channel second portion thereby causing rotation of a conducting fluid enveloped therein, and centrifugal force thereby developed causes the fluid in the bell-shaped portion to migrate into the fluid channel second portion and from thence into the fluid channel third portion from which the fluid is impelled outwardly.

4. In an electromagnetic fluid pump comprising a magnetic structure having a first and a second core element and a polyphase electric winding, and a fluid channel having a first, second and third portion; said first core element being elongated and of generally circular outer configuration in a direction normal to the elongation thereof, said second core element being elongated and of generally circular outer configuration in a direction normal to the elongation thereof, said fluid channel first portion being a bell-shaped duct supported adjacent a first end of the first core element, said fluid channel second portion being an elongated duct of generally circular shape in cross section nested between the first and second core elements, said bell-shaped duct being connected at its large end to a first end of the second duct portion, said fluid channel third portion being a flaring duct connected at the smaller end to a second end of the second duct portion, a circular magnetic extension element affixed to the second core element to overhang the first core element first end, and fluid conveying means connected to the inner end of the bell-shaped duct, means for electrically connecting the fluid channel first and third portions, whereby under a condition of electrical energization, a rotating field traverses part of the bell-shaped duct and the fluid channel second portion thereby causing rotation of a conducting fluid enveloped therein, and centrifugal force thereby developed causes the fluid in the bell-shaped portion to migrate into the fluid channel second portion and from thence into the fluid channel third portion from which the fluid is impelled outwardly.

gation thereof, said second core element being elongated and of generally circular inner configuration normal to the elongation thereof and having an inner boundary with a radius greater than the radius of the first core element by the thickness of the fluid channel second portion, said second core element being supported to surround the first core element, said electric winding being supported on at least one of the core elements to produce under a condition of energization a substantially radial rotating magnetic field, said fluid channel first portion being a bell-shaped duct supported adjacent a first end of the first core element, said fluid channel second portion being an elongated generally circular duct nested between the first and second core elements, said bell-shaped duct being connected at its large end to a first end of the second duct portion, said fluid channel third portion being a flaring duct connected at the smaller end to a second end of the second duct portion, a circular magnetic extension element affixed to the second core element to overhang the bell-shaped duct outer portion, a magnetic extension element affixed to the first core element and extending to the bell-shaped duct, and fluid

conveying means connected to the inner end of the bell-shaped duct, means for electrically connecting the fluid channel first and third portions, whereby under a condition of electrical energization, a rotating field traverses part of the bell-shaped duct and the fluid channel second portion thereby causing rotation of a conducting fluid enveloped therein, and centrifugal force thereby developed causes the fluid in the bell-shaped portion to migrate into the fluid channel second portion and from thence into the fluid channel third portion from which the fluid is impelled outwardly.
